UNITED STATES PATENT OFFICE

THOMAS F. PINDER, OF MERION, PENNSYLVANIA

PRINTING

Application filed December 26, 1930. Serial No. 504,946.

The principal object of the present invention is to improve the operation of printing and perfecting sheet delivery presses in such a way that offsetting is avoided or minimized, 5 without requiring the use of an offset web or any special covering on the impression surface, and without the requirement of slip sheets.

Another object of the invention relates to 10 the design and correlation of various devices and apparatuses whereby printed ink may be subject to chemical, electrical and mechanical action for setting and conditioning the same to enable the ink to withstand the 15 stresses to which it is subject in the various printing operations, thereby eliminating offsetting.

Another object of the invention resides in 20 the direct application of electrical discharges for the creation of ozone, light rays and vibrations that have beneficial effects upon the printer's ink for the obtainment of the objectives herein set forth.

A feature of the invention resides in the 25 direct application of radiant heat to the freshly printed ink for the creation of a preliminary condition, relying on a direct application of electrical discharges for final treatment of the ink and the production of ozone 30 and light rays having a direct reaction upon the constituents of the ink.

Generally stated, the invention comprises 35 a method and apparatus for preventing offsetting by subjecting a traveling web of paper having freshly printed ink thereon first to the action of radiant heat and then to the action of electrical discharges and the ozone and light rays created thereby, the web of paper being subjected to a cooling action at 40 the point of subjection to the electrical discharges.

With the above objectives in view and others obvious from a detailed consideration of the invention, the method will be better 45 understood from a detailed consideration of the accompanying drawing, wherein.

The figure is a diagrammatic view of one embodiment of the invention.

Having reference to the drawing, the numeral 1 designates a web of paper which in

its passage through the printing rolls 2 has arranged on its surface the printed matter. The freshly printed ink on the reach A passes through a heater 3, preferably of the electric radiant type embodying a plurality of deflectors 4 having a co-relation with the electric heating unit 5. I have found from actual practice that with this type of heater the reach of paper may be brought to the required temperature. It will be noted that there is a radiant heater arranged opposite each side of the web of paper so that simultaneously both sides of the paper is subject to a heating action to facilitate the effect and the uniformity of the action.

The reach A passing around the feed roll 6 has its temperature reduced by means of the collector 7. This collector 7 embodies a nozzle 8 for drawing air over the paper web and discharging the same through the conduit 9. It is of course to be understood that the web of paper may be subjected to other types of cooling devices, which may be arranged in convenient places other than illustrated.

The reach B of the web of paper with the partially conditioned ink thereon is passed through an ozonator 10, preferably of the electrical type so as to be self generating. In one of its forms this ozonator comprises a pair of wire grids 11 and 12 arranged on opposite sides of the reach B and paralleling the surfaces thereof and as these grids are of a metallic construction it will be appreciated that when subject to high potential currents through the leads 13 and 14, numerous electrical sparks will pass therebetween and through the web of paper, the latter acting as a di-electric to enable the potential of the electrical discharges to build up the required voltage. Due to the fact that the grids 11 and 12 are of a wide area and parallel the surfaces of the web of paper, it will be appreciated that the entire printed surface is subject to electrical discharges and as these electrical discharges produce simultaneously light rays and ozone and vibrations, 85

it will be understood that the printed ink is not only subject to a vibratory action due to the discharges but to the chemical action of 90 100

ozone and light rays as well, which greatly facilitate the final conditioning of the ink to prevent offsetting.

As there are advantages to be derived from cooling the web of paper as well as the generated ozone, I have illustrated a cooling apparatus 15 shown in this particular instance as consisting of cooling coils 16 connected to feed and discharge pipes 17 and 18.

10 I have found from actual practice that the objectives sought after can be more quickly and efficiently reached by first preparing the ink for a better reaction to the treatments heretofore set forth. To accomplish this, I 15 take a polymerizable oil such as tong oil and process the same to a stage that polymerization is greatly enhanced. This polymerization agent is then mixed with ordinary printing ink previous to a printing operation. In 20 the use of printing ink, conditioned as just set forth, polymerization reactions are enhanced and the time element considerably reduced.

In the use of my method of treatment, a 25 printed web of paper in its passage through the radium heater is subject to a high temperature preferably 300° F. which subjects the processed ink to a preliminary treatment for accomplishment among other things a 30 polymerization condition of the ink. This action also prepares the ink for a better reaction with the electrical treatments as above set forth.

The ink conditioned as just set forth is subject to a cooling action to more or less set the 35 same for a better reaction with the new electrical discharges, ozone and electric rays created by the ozonator.

The ink is passed through the ozonator 40 and subjected to a multiplicity of minute electric sparks which pass directly through the web of paper and through the contents of the ink for giving a final polymerization action and an oxidizing action thereto, thereby enabling the ink to withstand all stresses to which it is subjected in the passing of the web through its final operation. To facilitate matters, I provide a cooling apparatus 45 which not only cools the web of paper for giving a final set to the ink but prevents deterioration of the ozone generated, thereby prolonging its activity upon the printed ink.

In concluding, I wish to lay stress upon the fact that my specially prepared printing 55 ink is subject to mechanical, electrical and chemical actions for giving the ink the necessary resistivity to resist distortion or offsetting and this is accomplished in a unique manner by the use of an ozonator in a particular relation with the web of paper so that the web of paper will be simultaneously subjected to the action of ozone, electrical discharges and light rays, all three actions having a desired effect upon the ink for the final conditioning thereof.

It is of course to be understood that various types of heaters may be utilized and various types of ozonators may be used and the vibratory effects, light ray effects and ozone treatments applied in other manners and therefore I do not desire to be limited in protection in any manner whatsoever except as set forth in the following claims.

I claim:

1. A method of preventing offsetting in 75 printing machines which consists in simultaneously subjecting opposite sides of a printed web of paper to the direct action of heat and cold and electric light rays.

2. A method of preventing offsetting in 80 printing machines which consists in first treating ink to increase its polymerization action and then subjecting the same to the direct action of heat, chilled ozone and electric light rays.

3. A method of preventing offsetting in printing presses which consists in first subjecting the printed web of paper to the action of heated air contacting simultaneously with opposite sides of the web of paper and secondly to ozone and electrical discharges and thirdly to a cooling action.

4. A method of preventing offsetting in printing machines which consists in processing an oil to increase its polymerization action and mixing with stock ink and subjecting the ink when in printed condition first to the action of heat and then to the action of chilled ozone.

5. A method of preventing offsetting in 100 printing machines which consists in processing an oil to increase its polymerization action and mixing with stock ink and subjecting the ink when in printed condition first to the action of heat and then to the action 105 of chilled ozone, in the presence of electrical discharges.

6. A method of preventing offsetting of a printed web of paper which consists in subjecting the printed ink containing tong oil 110 to the action of radiant heat and then to the action of electrical discharges passing directly through the printed web of paper.

7. A method of preventing offsetting of a printed web of paper which consists in subjecting the printed ink containing tong oil 115 to the action of radiant heat and then to the action of electrical discharges passing directly through the printed web of paper, said web being subject to a cooling action while 120 acted upon by said discharges.

In witness whereof I have hereunto set my hand.

THOMAS F. PINDER.
